UNITED STATES PATENT OFFICE.

BENJAMIN FRANKLIN DUNHAM, OF MUSCATINE, IOWA, ASSIGNOR OF ONE-HALF TO ORVILLE M. MORRIS, OF DAVENPORT, IOWA.

DESIGN FOR A BLACKBOARD-ERASER POCKET.

SPECIFICATION forming part of Design No. 32,231, dated February 13, 1900.

Application filed January 18, 1900. Serial No. 1,939. Term of patent 7 years.

To all whom it may concern.

Be it known that I, BENJAMIN FRANKLIN DUNHAM, a citizen of the United States, residing at Muscatine, in the county of Muscatine and State of Iowa, have invented and produced a new and original Design for Blackboard-Eraser Pockets, of which the following is a specification, reference being had to the accompanying drawings, forming part thereof.

Figure 1 is a perspective view of the blackboard-eraser pocket, showing my new design. Fig. 2 is a section on line 2 2, Fig. 1; and Fig. 3, a section on line 3 3, Fig. 1, looking down.

As shown in the drawings, the leading or material feature of my design consists in a rectangular frame A, having a flange B at each side and a flange C at the bottom, each of

these flanges having double scallops in them, 20 the intermediate inwardly-projecting portion b (or c) between the scallops being of less depth than the flange, so that each flange is roughly M-shaped.

The opening a in the frame is filled with a 25 monogram or scrollwork "D."

Having thus described my invention, what I claim as new, and desire to secure by Letters Patent, is—

The design for a blackboard-eraser pocket 30 as herein shown and described.

In testimony whereof I have signed my name to this specification in the presence of two subscribing witnesses.

BENJAMIN FRANKLIN DUNHAM.

In presence of—

MAUDE BERRY,
T. R. FITZGERALD.
